WALTER O. LUM

INVENTOR

BY *L. Stewart Gatter*
AS HIS ATTORNEY

UNITED STATES PATENT OFFICE.

WALTER O. LUM, OF NEW YORK, N. Y., ASSIGNOR TO BLO-DRY INCORPORATED, OF SYRACUSE, NEW YORK, A CORPORATION OF NEW YORK.

FAN BLOWER.

Application filed December 2, 1924. Serial No. 753,472.

My invention relates to improvements in fan blowers of the type usually used in hot air drying machines and the like. The object of my device is to create a blower of this type which will be very simple and cheap in construction and at the same time will have a high mechanical efficiency. My fan type construction is an improvement over the so-called "Sirocco" type.

10 The further object of my invention is to provide a blower of this type which will be very rugged and at the same time lend itself to be readily balanced and develop little distortion under running conditions. My further purpose is to provide a construction which will permit the assembly of my fan blower so that the static balance and the dynamic balance can be obtained in the simplest and most inexpensive manner.

15 Furthermore it is my object to design a blower of this type which will permit drawing air from both sides of the blower housing which in turn permits drawing a portion of the air through the motor of a drying machine which in turn serves to keep the motor cool and also to deliver the motor heat to the air stream thereby supplementing the heat unit in the typical hot air drying device. In order that the invention may 20 be more fully understood reference is made to the accompanying drawings in which like letters refer to like parts.

Figure 1 is an end elevation of my device.

Figure 2 is a plan view showing a phantom section around the hub.

Figure 3 is a side elevation of a portion of an outer rim of my device showing angular spacings of the vane connections whilst Figure 4 is a plan view of the same.

Figure 5 is a side elevation of a portion of the central section of my device showing the vane slots and angular spacings whilst Figure 6 is a plan view of the same.

Figure 7 shows an enlarged development in side elevation of a single vane or bucket in my device whilst Figure 8 is an end view of the same.

In constructing my device I use two identical side discs or sections A and I.

Referring to Figure 1, the ends of the vanes or buckets B are shown in dotted lines. C and D are the holes in the end sections A and I where the end portions X and Y of

each bucket are connected whilst F is an empirical angle made between the center line of the disc and the line through the center of the holes C D which is designated by the letter E. This angle I have worked out by numerous careful experiments and the result which I have determined develops a blower giving very great velocity with a minimum noise.

Referring to Figure 2, J is a key-way for an auxiliary drive coupling. G is the end of the axis bearing or hub K whilst L is a shoulder holding the whole, turning with the shaft M, whilst I is the other outer section.

In Figure 3, O is another empirical angle made by lines from the center of rotation point to each of the vane supporting holes in the outer sections, whilst line N represents one of the lines through the center point of rotation and the inner vane supporting hole.

Referring to Figure 5, T is the axial hole in the central disc H, P being the circle passing through the base of the slots S—S—S, Q representing one center line of said slots and R being the angle between lines Q and the center line of rotation where same cuts the outer circle of the central disc, the angle R being another empirical angle.

Referring to Figure 7, one enlarged bucket B is shown with the slot V which feeds into the slots S of the center disk said slot V does not cut either edge of the bucket or blade B whilst end protrusions X and Y feed into the holes C and D in the end sections, U and W butting solidly up against the end section whilst in Figure 8, line Z represents a radius of curvature of each bucket. It will be seen that my device comprises a center disc or plate H which carries a series of buckets in slots in its periphery and that these buckets are held in place by annular side rings attached to the bucket ends. The buckets themselves are provided with cross-wise slots V at a center point to locate them properly on the central disc. My hub may be integral with the central disc H or may be a separate piece attached thereto in suitable manner. It will appear that the hub of my blower supports the central disc, and that the central disc supports the vanes, and that the vanes support the two outer annular rings.

Having thus described my invention what I claim and desire to secure by United States Letters Patent is:

1. In a fan blower, the combination of a shaft, a hub for said shaft, a circular central disc for said hub containing a series of spaced open slots about its periphery, curved blades having closed slots at a central section, and registering with said slots in said central disc and having projections at each end, annular outer rings containing means for receiving and holding the projections of said curved blades, all as and for the purposes hereinbefore described.
- 15 2. In a fan blower, the combination of a shaft, a hub for said shaft, a circular central disc for said hub containing a series of spaced open slots about its periphery, the center line of said slots being at an angle to the radial lines of said disc, curved blades having closed slots at a central section, and registering with said slots in said central disc and having projections at each end thereof, annular outer rings containing

means for receiving and holding the projections of said curved blades, all as and for the purposes hereinbefore described.

3. In a fan blower, the combination of a shaft, a hub for said shaft, a circular central disc for said hub containing a series of spaced open slots about its periphery, the center line of said slots being at an angle with the radial lines of said disc, curved blades having closed slots slotted at a central section, and registering with said slots in said central disc, and having projections at each end, two annular outer rings, each containing an outer and an inner series of holes to receive projections at the ends of said blades, the radial lines connecting the centers of said inner holes making angles with the radial lines of said outer holes, all as and for the purposes hereinbefore described.

In witness whereof, I have signed my name to these specifications this 19th day of September, 1924.

WALTER O. LUM.
